INVENTORS

UNITED STATES PATENT OFFICE.

FRANK HOLUB AND CHARLES S. LOCKE, OF CHICAGO, ILLINOIS.

MACHINE FOR BENDING HORSESHOE-BLANKS.

SPECIFICATION forming part of Letters Patent No. 242,535, dated June 7, 1881.

Application filed September 20, 1880. (No model.)

To all whom it may concern:

Be it known that we, FRANK HOLUB and CHARLES S. LOCKE, of Chicago, in the county of Cook and State of Illinois, have invented 5 certain new and useful Improvements in Machines for Bending Horseshoe-Blanks, of which the following is a specification.

In forming horseshoe-blanks by machinery the toe-calk is usually formed flush with the 10 front side of the blank, so that when the blank is bent the front of the toe-calk is curved and is flush with the curved front end of the shoe, and is thus unlike hand-made shoes, the toe-calks of which are usually straight.

15 It is the object of our invention to bend a machine-made horseshoe-blank, and in the process of bending to straighten up the toe-calk and swage it a little back from the front edge of the bent blank, as shown in Fig. 9, as if it 20 were made by hand. Our machine is capable of so bending the blank and shaping the toe-calk, when the blank is formed with the toe-calk flush with its front side, as above stated; but we have devised a machine, for which we 25 have made application for Letters Patent, for forming a horseshoe-blank with its toe-calk a little back of the front edge of the blank, as shown in Fig. 8, and that is the sort of blank we particularly contemplate bending and swaging in the present machine.

30 In the accompanying drawings, which illustrate our invention, Figure 1 is a plan view. Fig. 2 is also a plan view of one end of the machine, showing the bending-jaws and bending-die in a different position. Fig. 3 is a side elevation. Fig. 4 is a longitudinal central section on the line 4 4 of Fig. 1. Fig. 5 is a transverse section on the line 5 5 of Fig. 1. Fig. 6 is a transverse section on the line 6 6 of Fig. 40 1. Fig. 7 is a perspective view of the under side of the bending-die. Fig. 8 is a plan view of the blank, and Fig. 9 is a plan view of the bent blank.

45 A indicates the bed of the machine, which may be supported in any suitable solid framework. Within the center of this bed is a reciprocating plunger, B, working in suitable guideways, C, and carrying upon its outer end a bending-die, D, and a toe-calk-swaging die, E. This plunger is actuated by means of the 50 heavy crank-shaft F and the pitman G, to which motion may be given by any suitable prime mover.

H H indicate bending-jaws, the function of which is to partially close around the bending-die, clamping the horseshoe-blank, which is forced between them by the plunger. These jaws are pivoted at I I, and provided with guide-pins K K, which project beneath them into suitable guide-slots in the table. They 60 are also provided with friction-rollers L L, which bear against the horseshoe-blank in the process of bending.

M M indicate friction-rollers on the outside of the jaws, against which bear the sliding 65 cams N N, actuated by the rods or bars O O, which are reciprocated at proper intervals by cams P P upon the main driving-shaft.

Q indicates a fixed but adjustable die or plunger, coincident with the calk-swaging die 70 E. This plunger is made adjustable by means of the heavy set-screws, (clearly shown in Figs. 1, 2, and 4 of the drawings,) as will be understood without further explanation.

The operation of our machine is as follows: 75 Assuming the bending-jaws to be open and the bending-die D to be retracted, as shown in Fig. 1, the blank is placed in position before the jaws and in front of the bending-die, as clearly shown in Fig. 1. A half-revolution 80 of the driving-shaft will force the blank between the dies and curve it around the bending-die, its heel portions being last bent by the abrupt action of the sliding cams N N at 85 the same instant that the calk is swaged by the last part of the forward thrust of the plunger. As the rotation of the driving-shaft continues the bending-die carrying the bent blank will be retracted, the jaws opened, and as the die comes over the open space in the 90 center of the table into the position shown in Fig. 1 the shoe will drop off into any suitable receptacle; or, if any difficulty is found in releasing it by gravity, any ordinary appliance for picking it off from the die may be employed. The finished bent blank will have the conformation exhibited in Fig. 9, the toe-calk being straight and not flush with the front

edge of the shoe, as is usual with machine-made bent horseshoe-blanks, but being like a hand-made blank.

Having thus described our invention, what we claim as new, and desire to secure by Letters Patent, is—

The bending-die D, in combination with the

toe-calk-swaging die E and the adjustable plunger Q, substantially as described.

FRANK HOLUB.
CHARLES S. LOCKE.
